[57] CLAIM

The ornamental design for a luminaire, as shown and described.

DESCRIPTION

FIG. 1 is a front elevational view of a luminaire in accordance with the present invention;

FIG. 2 is a left side elevational view of the luminaire of FIG. 1, with the right side elevational view being a mirror image thereof;

FIG. 3 is a rear elevational view of the luminaire of FIG. 1;

FIG. 4 is a top plan view of the luminaire of FIG. 1; and FIG. 5 is a bottom plan view of the luminaire, the facets on the diffuser being partially shown for convenience of illustration, it being understood that the facets are continuous around the area on which they appear.

FIG. 1

FIG. 2

FIG. 3

FIG. 4

FIG. 5
